UNITED STATES PATENT OFFICE.

ROBERT H. ISBELL, OF WOODLAWN, NEW YORK.

COMPOUND ROTARY ENGINE.

SPECIFICATION forming part of Letters Patent No. 586,497, dated July 13, 1897.

Application filed December 4, 1896. Serial No. 614,425. (No model.)

To all whom it may concern:

Be it known that I, ROBERT H. ISBELL, a citizen of the United States, residing at Woodlawn, in the city, county, and State of New York, have invented a Compound Rotary Engine, of which the following is a specification.

This engine is made for using the steam expansively, and with this object in view the pistons are compound and pivoted, the inner leaf of each piston resting at its edge against a stationary hub that is approximately round, and the outer leaf of the piston travels against the interior surface of the case, and these pistons, preferably three in number, are connected with a cylinder that is supported by a head and a shaft from which the power is taken, and the hub and case are eccentric to the rotary cylinder, so that there are inner and outer steam-chambers, the inner leaves of the pistons being acted upon within the inner steam-chamber by high-pressure steam and the outer leaves of the pistons being acted upon in the outer chamber by the steam as it expands, and the same finally passes off at the exhaust. In this engine the two steam-chambers are crescent-shaped and stand in reverse directions.

In the drawings, Figure 1 is a cross-section through the engine. Fig. 2 is a section upon the line 2-2 of Fig. 1. Fig. 3 shows the interior surface of the case with the inlet-steam port and the transfer-port. Fig. 4 is a side view of the cylinder and outer pistons. Fig. 5 is an end view of the shaft and cylinder. Fig. 6 shows the inner side of the removable head, and Fig. 7 is a sectional illustration of the passage for the steam that first acts on the outer piston.

The case of the engine is made with a stationary head A and a nearly cylindrical or barrel portion B, and there is a removable head C, that is bolted upon the case at 5, and this removable head C carries the hub D.

The main shaft E passes through the gland or stuffing-box 6 and is supported in a socket within the hub D, and there is advantageously an axial hole 7 for the insertion of oil. Projecting from the main shaft E and preferably made with the same is the head F, to which is permanently connected the cylinder G, which is made up of three parts permanently connected at one end to the head

F and at the other end to the ring 8, which ring 8 is supported by and travels in a circular groove in the removable head C, and in consequence of the interior of the barrel B being eccentric to the shaft E and approximately circular there is a crescent-shaped steam-chamber 9 between the outer surface of the cylinder G and the interior of the barrel or case B, the cylinder G setting closely against the interior surface of the case B at one side and the hub D setting closely against the interior surface of the cylinder G at the other side, and such hub being eccentric to the cylinder G there is a crescent-shaped steam-chamber 10 between the hub D and the interior of the cylinder G, and it is now to be understood that the chamber 10 is for high pressure and the chamber 9 for low pressure, the steam acting expansively in the latter.

The pistons H are each advantageously made with an inner leaf 11 and an outer leaf 12 and supported upon a pivot-pin 13, and this pivot-pin 13 passes through the ring 8 into the head F, and these pistons set closely, so as to be substantially steam-tight at the cylindrical or hinge portion of each piston, and the inner leaf 11 is smaller than the outer leaf 12, the chamber 9 being wider than the chamber 10, and it is to be understood that the distance between the outer edge of the leaf 12 and the inner edge of the leaf 11 corresponds, or nearly so, to the distance between the inner surface of the case B and the outer surface of the hub D at the places of contact, so that as the pistons travel around with the cylinder G their edges remain in contact, or nearly so, with the surfaces named.

The outer surfaces of the cylinder G are recessed, so as to allow the outer leaves 12 of the pistons H to pass into such recesses as the cylinder moves past the abutment 14 or point of contact of the cylinder G with the interior of the case B, and the inner surfaces of the cylinder G are also recessed to receive into them the inner leaves 11 of the pistons as the cylinder passes the abutment 15 or point of contact between the hub D and the inner surface of the cylinder G.

The live steam under the proper pressure is admitted by the pipe I, and the exhaust pipe K opens into the chamber 9 near one end of the said crescent-shaped chamber. The

inlet-steam pipe I opens into a port 16, which is in the stationary head A and extends part way around the same as an arc of a circle, and there is a similar-shaped transfer-port 17 5 in the head A, and a branch 18, passing from such transfer-port and opening into the case B near the opposite end of the steam-chamber 9 to the exhaust-port K.

Through the head F are ports 19, there being one port for each of the three pistons, and the parts are so positioned that as the cylinder G, head H, and pistons revolve high-pressure steam is admitted through one of the ports 19 from the steam-ports 16, and the high-pressure steam acts between the abutment 15 and one of the inner leaves 11 to carry the pistons and cylinders in the direction indicated by the arrow, and the pressure continues active within the high-pressure 15 chamber 10 until another piston is brought around into position for steam to be admitted by the next port 19 to act upon such inner leaf 11 and continue the movement, and the high-pressure steam is cut off from the first-named piston when its port 19 reaches the end of the steam-port 16, and the port 19 passes over the inner surface 20 between the end of the steam-port 16 and the commencement of the transfer-port 17, and as soon as 20 such port 19 reaches the transfer-port the high-pressure steam in the inner chamber 10 passes through such transfer-port 17 and the branch 18 into the steam-chamber 9 to act upon the outer leaf 12 of one of the pistons, which at this moment has been brought into 25 proper position for the force of the expanding steam to be exerted upon the larger and outer leaf of the piston to carry the same around to the exhaust-pipe K, and one piston 30 is fully in operation by the expanding steam when the piston that is in front of it reaches the exhaust-port, so that there is no back pressure behind the piston that is in full operation, and so also the pressure acts in its 35 full power upon the inner leaf of one piston during the time that the high-pressure steam is passing out from the preceding high-pressure-steam chamber through the transfer-port, and by using three pistons, each having 40 two leaves, the circle is advantageously divided up into sections of one hundred and twenty degrees, and the outer leaf of one of the three pistons is at the point of greatest power at the time the inner leaf of the next 45 succeeding piston is going out of action and the inner leaf of the third piston is coming into action, the inner leaves of the pistons exerting their greatest force as the outer leaf of one piston is coming into action and the 50 outer leaf of the other piston is going out of action, so that the power exerted all around the main shaft E to rotate the same is uniform, or nearly so, at all places.

In some instances I have used the engines 55 with only the parts hereinbefore described; but I find it advantageous to employ in addition ports for admitting steam to act be-

tween the cylinder G and the outer leaf to press the edge of such outer leaf against the interior of the case B and other ports to admit steam between the inner leaves 11 of the pistons and the interior surfaces of the cylinder G to press the edges of such inner leaves into contact with the exterior surface of the hub D and thereby prevent the escape 75 of steam at the respective places and prevent any hammering action that might arise from looseness of the respective parts; and with this object in view I provide channels or ports a in the inner surfaces of the cylinder G at 80 the bottom of the recesses into which the inner leaves 11 of the pistons are received, and these channels a open at their ends by lateral holes into the ports 19, so that steam will pass through these ports 19 and channels a and 85 act to press the inner leaves of the pistons in succession, so that they rest against the outer surface of the hub D before the full force of the steam admitted through one of the ports 19 acts between the inner leaf and the abutment. I also provide a channel or port c in the bottom of each of the recesses receiving the outer leaves of the pistons, and these channels c open at their ends through the head F, and it is important to admit live 90 steam to act in these channels c, and with this object in view I make a U-shaped port 21 in the stationary head A between the end of the steam-port 16 and the beginning of the transfer-port 17, and the parts are so proportioned that as soon as one port 19 passes the end of the steam-port 16, so that the surface 20 closes the port 19, the confined high-pressure steam may pass through that port 19 and through the U-shaped port 21 and back 100 through and into the hole at the end of the channel c, and in so doing the high-pressure steam will act to move the outer leaf of one piston H out of its recess, so that its outer edge bears against the inner surface of the 105 case B before the port 19 reaches the commencement of the transfer-port 17. Hence as soon as this port 19 does reach the commencement of the transfer-port 17 the high-pressure steam in the chamber 10 passes 115 through such port 19 into the transfer-port through the branch port 18 and acts within the outer steam-chamber 9 against the outer leaf of the piston, which has by the aforesaid movement been brought into position for the 120 steam to expand and exert its force against that piston in continuing the movement of the cylinder G and its shaft.

The aforesaid operations being performed in succession the full force of the expanding 125 steam is in operation, as the efficiency of the high-pressure steam upon the inner leaves diminishes and the efficiency of the high-pressure steam upon the inner leaves of the pistons increases as the efficiency of the expanding pressure diminishes on the outer leaves, thus equalizing the power exerted to rotate the main shaft, and either the high pressure or the low pressure is always opera- 130

tive on each piston, there being two pistons acted upon by high pressure and one by low pressure, or the reverse. Hence power is always acting all around the shaft to equalize strain and wear.

The engine is very simple, as there are but few parts to construct, and they are not liable to get out of order or to wear rapidly, and the full benefit of expansion is obtained.

10 I claim as my invention—

1. In a rotary engine, the combination with the case and its heads and a stationary hub carried by one of the heads, of a main shaft and its head, a cylinder carried by the head and pistons at equal distances around the cylinder each having a leaf projecting inward and a leaf projecting outward, there being a port for the high-pressure-steam ports in the revolving head through which the high-pressure steam passes to act upon the inner leaves of the pistons, a transfer-port for the high-pressure steam to pass from the inner chamber to the outer chamber, and act upon the outer leaves of the pistons, and an exhaust port from the outer chamber, substantially as set forth.

2. The combination in a rotary engine, of an outer case and its heads, a hub carried by one of its heads, a shaft eccentric to the hub and a head upon such shaft, a cylinder composed of sections and intermediate pistons having inner and outer leaves, a ring for connecting the sections of the cylinder together and pivot-pins passing through the ring and head and upon which the pistons swing, a steam-inlet port, and ports through the head to which the cylinder is connected, a segmental transfer-port and branch for allowing high-pressure steam from the inner chamber to pass into the outer chamber, and an exhaust pipe or port from the outer chamber, substantially as set forth.

3. The combination in a rotary engine, of

a main shaft and head, a cylinder supported by such head and pivoted pistons in the cylinder having inner and outer leaves, the cylinder being recessed for the reception of such leaves, and ports or pipes for allowing steam to pass into the recesses and beneath the respective leaves of the pistons for moving such leaves outward or inward to bring their edges into contact with the interior surface of the case or the exterior surface of the hub, substantially as set forth.

4. The combination with the case and its heads, of a hub carried by one of the heads, a main shaft, cylinder and pistons carried by such shaft, the pistons having inner and outer leaves to act within the crescent-shaped steam-spaces between the cylinder and the case, and the cylinder and the hub respectively, the cylinder being recessed for receiving the leaves of the pistons, steam-ports for admitting pressure into the recesses for swing-
ing the respective pistons out of such recesses and a U-shaped port in the head of the case for allowing such steam-pressure to act in moving the outer leaves of the pistons out of their recesses, substantially as set forth.

5. The combination in a rotary engine, of a stationary case and a stationary central hub, an intermediate cylinder placed eccentric and pistons passing through and pivoted upon the said cylinder and having one leaf acted upon by pressure in the inner chamber and the other leaf by pressure in the outer chamber, there being recesses into which one leaf of each piston is swung while the other leaf is in action, substantially as set forth.

Signed by me this 30th day of November, 1896.

ROBERT H. ISBELL.
